US00D662912S

(12) **United States Design Patent**
Iijima et al.

(10) **Patent No.:** **US D662,912 S**
(45) **Date of Patent:** **** Jul. 3, 2012**

(54) **HEADSET**(75) Inventors: **Yoshimune Iijima**, Tokyo (JP); **Daisuke Iseki**, Tokyo (JP)(73) Assignee: **Sony Corporation**, Tokyo (JP)(**) Term: **14 Years**(21) Appl. No.: **29/371,658**(22) Filed: **Jun. 27, 2011****Related U.S. Application Data**

(63) Continuation-in-part of application No. 29/347,987, filed on Sep. 3, 2010, now Pat. No. Des. 644,625.

(30) **Foreign Application Priority Data**

Mar. 2, 2010 (JP) D2010-005420

(51) **LOC (9) Cl.** ..... **14-01**(52) **U.S. Cl.** ..... **D14/205**(58) **Field of Classification Search** ..... Primary Examiner — Paula Greene(74) *Attorney, Agent, or Firm* — Rader, Fishman & Grauer PLLC(57) **CLAIM**

The ornamental design for a headset, as shown and described.

DESCRIPTION

FIG. 1 is a perspective view of a first embodiment of a headset showing our new design;

FIG. 2 is a front elevational view thereof;

FIG. 3 is a rear elevational view thereof;

FIG. 4 is a right side elevational view thereof;

FIG. 5 is a top plan view thereof; and

FIG. 6 is a bottom plan view thereof.

FIG. 7 is a perspective view of a second embodiment of a headset showing our new design;

FIG. 8 is a front elevational view thereof;

FIG. 9 is a rear elevational view thereof;

FIG. 10 is a right side elevational view thereof;

FIG. 11 is a top plan view thereof; and,

FIG. 12 is a bottom plan view thereof.
